Inventor.

Adam Knacker.

United States Patent Office.

ADAM KNACKER, OF MEADVILLE, PENNSYLVANIA.

Letters Patent No. 101,744, dated April 12, 1870.

IMPROVEMENT IN SINK APPARATUS FOR DRAINING CELLARS.

The Schedule referred to in these Letters Patent and making part of the same

To all whom it may concern:

Be it known that I, ADAM KNACKER, of the city of Meadville, in the county of Crawford and State of Pennsylvania, have invented a new and improved "Mode of Draining Cellars;" and I do hereby declare that the following is a full and exact description of the same, reference being had to the accompanying drawings and the letters of reference marked thereon.

A A represent the cellar-walls.

B B, the bottom.

C C is a sink in the bottom, of which there may be a number sunk in the same cellar, if desired.

In the bottom of this sink I drive a pipe, D D, with the lower end plugged and pointed, similar to the well-pipes now in use; and the lower end of this pipe is perforated with holes, as shown in the drawing.

In that portion of the pipe just above the bottom of the sink C C, I put an elbow of pipe, with a stainer on its upper end, as shown at F.

E is a stop-cock in the elbow.

The pipe D D is driven into the ground until it reaches a bed of gravel.

On the upper end of the tube D a pump is placed,

and operated until the pump draws water. The stop-cock E is then opened, and, if it is desired, the pump may be removed.

Now, should there be any water in the cellar, it will run into the elbow at F, and down through the tube D D, and drain off into the gravel at the bottom of D D.

This device is in successful operation in a number of cellars.

Should the holes in the bottom of D D become filled with "mud," by placing a pump on the top of the tube D, and operating it again, the tube may be cleared.

I do not claim the pump and tube D D, but

What I do claim, and desire to secure by Letters Patent, is as follows, to wit:

The elbow F, in combination with the sink C C and the tube D D, constructed as described, for the purposes set forth.

ADAM KNACKER.
